(57) **CLAIM**

We claim the ornamental design for a medical implant set, as shown and described.

DESCRIPTION

FIG. 1 is a front, bottom, right perspective view of a medical implant set, showing our new design;

FIG. 2 is a front elevational view thereof; and

FIG. 3 is a rear elevational view thereof.

FIG. 4 is a left side elevational view thereof;

FIG. 5 is a right side elevational view thereof;

FIG. 6 is a top plan view thereof;

FIG. 7 is a bottom plan view thereof;

FIG. 8 is a front exploded view thereof;

FIG. 9 is a front, top, right perspective view of FIG. 8; FIG. 10 is a front elevational view of another embodiment of a medical implant set, showing our new design;

FIG. 11 is a partial transparent perspective view of FIG. 10; the dashed lines used in FIG. 11 are for the purpose of being able to see the internal carrier; therefore the parts defined by dashed lines shall also be part of the subject design;

FIG. 12 is a front elevational view of another embodiment of a medical implant set, showing our new design;

FIG. 13 is a cross sectional view taken along Line A-A of FIG. 10; and,

FIG. 14 is an enlarged partial view of FIG. 13.
